Des N° 2182

10-10-1865

Nicholas Barrolier of Philadelphia Penna.
Letter Patent No. 3182. Dated Oct. 10. 1865.
Design for a Plan Dial.

The schedule referred to in this Letter Patent and making part of the same
shall whom it may concern.

Bes it known that I, Nicholas Barrolier, of the
City of Philadelphia and State of Pennsylvania, have invented a
new and useful design for Plan Dials, and I hereby declare the
following to be a full and exact description of the same, reference
being had to the annexed drawing, making a part hereof, which
represents the design intended to be imprinted in, or etched on
any similar material, and burnt or baked on to it. The design
represents various concentric circles.

Within the outer two circles are contained the numbers
representing the hours of the Solar time, commencing at 4 o'clock
in the morning and ending at 8 o'clock in the evening.

Within the four next circles are contained the hours,
half hours, quarter hours and minutes, showing the solar time for the
latitude of the place for which it is adapted.

Within the next two circles are shown the objects of
the equation of time table.

Within the next ten circles are shown the months
and days of each month throughout the year, and the number of
minutes and seconds corresponding to each day that the clock is faster
or slower than the dial, the lines of demarcation for which appear
between the two first circles of the ten circles already mentioned.

Within the next two circles are shown the names
of the Zodiacal Signs.

Within the next circles are shown the animals
represented in the Zodiacal signs of the Heavens.

Within the next circle are shown the months
and the part of a day of the month showing the places in which
each of the Zodiacal signs appear on the ecliptic.

Within the remaining circles are shown the thirty

two cardinal points of the Mariner's compass.

Having thus described my improved dial, what I
claim as my invention, and desire to secure by Letters Patent is,

The design to be printed upon or baked on: porce-
lain or its equivalent for a sun-dial, substantially as above de-
scribed.
